YARN TENSIONING DEVICE FOR KNITTING MACHINES

Fred Autem, Wyomissing, Pa., assignor to Textile Machine Works, Wyomissing, Pa., a corporation of Pennsylvania

Application May 23, 1935, Serial No. 22,952

27 Claims. (Cl. 66—146)

This invention relates to means for controlling the tension of the yarn of a knitting machine, and particularly to a device of this character for operation in a full-fashioned knitting machine.

Devices heretofore employed for controlling yarn tension, particularly of the finer two and three thread silk yarns frequently used in knitting, have been found objectionable for many reasons, among which is an excessive drag on the thread after passing through the yarn tensioning mechanism, frequently resulting in detrimental and irregular tensioning during the feeding of the yarn through the usual thread tensioning devices.

The prior devices, particularly those employed in full-fashioned machines, fail to maintain the threads sufficiently taut, so that, when a carrier, associated with a particular yarn, is inactive, or is moved to effect an idle course, the mere oscillation of the so-called "snappers", on the yarn-supporting shelf or rod, is often sufficient to cause the tension ring to withdraw the yarn from its bobbin, and the ring to drop to an inoperative position. This removes all tension from the yarn, causing loose loops along the selvedge edge to a point where the slack was taken up and tension was again being applied to the fabric.

One object of the invention is to eliminate sleness or washboard effects in the stocking fabric caused by irregular feeding of yarn to the needles of the machine.

Another object is to produce tighter and therefore more perfect selvedge edges in a stocking fabric.

Among the other objects of the invention, are to provide a novel yarn tensioning device for eliminating the above and other objectionable features of the prior art structures; to provide a device of this type which is particularly adapted for use in connection with straight knitting machines, for effecting even and steady feeding of yarn at all times, and at all portions of a thread carrier stroke, for producing a better and more uniformly looped selvedge, for causing the yarn to be laid across the sinkers and dividers with an even tension for aiding in giving the loops the same size and shape, and for avoiding the disadvantages of the usual cumbersome apparatus employed for regulating thread tension in a straight knitting machine; and to provide a unitary effective tensioning device of economical manufacture which may be readily attached to, and detached from, a fabric-forming machine without disturbing the fabric-forming elements.

The invention is herein described as employed in connection with a multi-thread or "ringless" silk stocking knitting machine wherein it is especially desirable, in view of the more popular and constantly growing demand for sheer stockings, to avoid variations in tension of the silk as it is fed to the needles. Apparatus of this type thus, prevents local variations in the length of the stitches caused by varying tension.

A further object of the invention is therefore, to provide means for uniformly and equally tensioning a plurality of like yarns, particularly as adapted to keep uniformly taut, each yarn of a three-carrier "ringless" hosiery thread supply.

With these, and other, objects in view, which will become apparent from the following description of an illustrative and practical embodiment of my invention, shown in the accompanying drawings, the invention comprises the novel elements, features of construction and arrangement of parts in cooperative relation, as herein-after more particularly pointed out in the claims.

In the drawings:

Figure 1 is an end view, with certain parts in elevation and section, and others indicated by broken lines, of a portion of a full-fashioned knitting machine, and a tension device of the invention in association therewith;

Fig. 2 is an enlarged end elevational view, partially in section, of the tension device, as viewed near the upper left center of Fig. 1;

Fig. 3 is a view, in side elevation, of the device of Fig. 2, taken at right angles thereto, as viewed from the front of the knitting machine;

Fig. 4 is a view, taken substantially along the line 4—4 of Fig. 2;

Fig. 5 is a view, similar to Fig. 4, of a modified form of the structure thereof;

Fig. 6 is a top plan view of the device as projected from Fig. 2, indicating yarns, for tensioning thereby, in positions assumed under certain tension conditions;

Fig. 7 is a view, similar to a portion of Fig. 6, of the device thereof, indicating one of the yarns in a position assumed under another tension condition;

Fig. 8 is a view, in longitudinal section, of a modification of one of certain elements of the previous figures for imposing a retarding action on the yarn;

5 Fig. 12 is a view, similar to Fig. 4, of the mechanism of Figs. 10 and 11;

Fig. 13 is a view, similar to Fig. 6, of the structure of Figs. 10, 11 and 12, with yarns as positioned relative thereto under certain tension conditions;

10 Fig. 14 is a view, similar to Figs. 7 and 9, of the device of Figs. 10, 11, 12 and 13, with yarns as positioned under other tension conditions;

Fig. 15 is a view, taken substantially along the 15 line 15—15 of Fig. 13, indicating the position of parts under certain yarn-tension conditions;

Fig. 16 is a view, similar to Fig. 15, of the parts thereof as positioned under other yarn-tension conditions;

20 Figs. 17 and 18 are views, similar to Figs. 15 and 16, respectively, of a modification of the structure thereof, indicating parts as positioned under corresponding yarn-tension conditions; and

25 Fig. 19 is a view, similar to Figs. 15 and 17, of a further modification of the structures thereof, and indicating the parts as positioned under similar conditions of yarn tension.

In practicing the invention, the yarn is drawn 30 from a cone or supply, and passed through the device of the improvement to a yarn carrier for distribution to the needles and other knitting parts. Ordinarily the yarn readily pulls off the cone, without undue tension, but with considerable variation. However, the tension sometimes becomes sufficiently great to break the yarn.

When the yarn, between the cone and the tension device of the invention, is slack or free from appreciable retardation against pulling from the 40 cone, the device exerts its maximum retarding force against feeding the yarn to the needles and other working parts. When the retarding force on the yarn, between the cone and the tension device is at a maximum, the device exerts a minimum of retarding effect against its feeding to the 45 needles. When the force required to pull the yarn from the cone is less than the maximum, or greater than the minimum, the retarding effect on the yarn by the tension device is accordingly 50 greater or less; the device thus operating reciprocally and gradually, between all values of pulling forces, from maximum to minimum, to exert a corresponding retarding effect, so that, irrespective of variations in pulling forces, between 55 maximum and minimum, from the yarn supply to the device of the invention, the pulling force between the device and the yarn carrier is maintained substantially constant.

Referring to the drawings, in Fig. 1, the sole 60 figure showing parts of a knitting machine with which the invention is adapted to operate, only the parts of such machine necessary to a complete understanding thereof in cooperation with the tension device, are therein shown, the other parts 65 and the operation thereof being well known in the art, as fully shown and described in the "Reading" Full Fashioned Knitting Machine Catalogue, copyright 1929, and published by The Textile Machine Works, Reading, Pennsylvania.

70 As indicated in Fig. 1, a yarn 22 is supplied from a cone 23, in a moistening box 24, through an eyelet 25, over a yarn-guide rod 26, through a tension device T, into a moistening trough 27, through a tension ring 28 and a snapper 29, 75 and over another thread-guide rod 32 to a yarn-

carrier arm 33. The carrier 33 lays the yarn 22, in a usual and well-known manner, to knitting mechanism including needles 34, on a needle bar 35, and a sinker-head assembly S.

In the above-described structure, the yarn 22 5 is pulled by the carrier 33, and, as above indicated, so long as the yarn pulls easily off the cone 23, the device T exerts a predetermined retarding effect to the yarn feed, to have the yarn, between the device T and the carrier 33, under a predetermined tension. If the yarn is pulled with difficulty off the cone, thereby increasing its tension between the cone and the device, the latter decreases its retarding effect, so that variations in the yarn tension, between the cone 23 and the 15 device T, are not transmitted to the yarn between the device T and the carrier 33.

To accomplish this result, in the preferred form of the invention, shown in Figs. 1, 2, 3, 4, 6 and 7, the device T is constructed of substantially T- 20 shape, in end elevation, as viewed in Fig. 2, having an upright leg 36, and a top horizontal cross head 37, of a cast-metal base. The head 37 is of vertical-wall, crate-like character having three rows 41, 42 and 43, each of three compartments, 25 the compartments of the rows 41 and 43 of which have open tops and bottoms, and the compartments of the row 42 of which have open tops and closed bottoms 44. The row 42, is longitudinally partially offset from the rows 41 and 43, at opposite sides thereof, to accommodate yarn-retarding elements 45 in proper relation to the yarns 22.

As more clearly seen in Figs. 2 and 4, the 30 row of compartments 42 is provided, beneath its transverse end and intermediate partitions extending in the general direction of the yarn, with slots 46 for the endwise reception of a strip or plate 47 including a series of raised portions 48 having high top surfaces disposed one intermediate the ends of each compartment of the row, 40 on which the yarn 22 is normally adapted to be acted upon, with variable degrees of retardation, by the elements 45.

The low top surfaces of the strip 47, between the raised portions 48, and at the ends of the 45 strip, gradually merge into the high top surfaces along easy curves, at the intersection of the high and low surfaces. Means, such as a set screw 49, may be provided for holding the strip 47 in place.

The elements 45, as better shown in Fig. 4, are 50 preferably of a construction whereby the yarn engaging surface is of vitreous material, such as provided by a glass tube having rounded in-turned ends one of which cooperates with the 55 curved surface between the adjacent low and high top surfaces of the strip to provide easy entrance of the yarn between the element and the high surface, and are also preferably in rotatable floating position on the yarn, and pivotally movable transversely to their lengths by the yarn, on the shoulder between the high and low top surfaces at the right of each compartment, as viewed in Fig. 4. By comparison of the wall thickness of one of the elements 45 of Fig. 4, 60 with a similar element 45a, of Fig. 8, it is seen that the weight on the yarn may be changed for different yarns or working conditions by substituting these elements one for the other.

Also, as seen in Fig. 5, the strip 47a, corresponding to the strip 47, is provided with a vitreous surface material 52, so that, in its operation between the elements 45 and 47a, the 70 yarn is not touched by metal. Eyelets 53, preferably of porcelain or glass, are provided in the 75

farthermost side walls of the rows 41 and 43 for leading the yarn through the device.

On the leg 36, knurled-head studs 54, held by washers 55 and nuts 56, adjustably secure the lower ends of elongated or wire-like springs 57, which extend through the studs in fixed relation thereto and are spaced from the leg by washers 58. The upper ends of the springs 57 protrude through the compartments 41 for lateral impingement against the yarns. Notches 59 constitute means whereby, in mounting the springs 57, they may all be mounted alike, or adjusted to different angles such that, when bent backwardly to the left, as indicated in Fig. 3, and released to impinge against the yarns, they will exert a preselected force against the yarns, it being understood that the notches are utilized only as reference marks in adjusting the device. Means, such as jaws 62, constituting integral dependent portions of transverse partitions 63, are provided for mounting the device T on one side wall 64 of the trough 27.

Each of the elements 45, together with its associated spring 57, the corresponding raised portion 48 of the strip 47, and other parts, constitutes a tension unit individual to its yarn 22, so that the device may be formed solely in individual unit form for single yarn applications, but, as shown, three of such units are cooperatively related, on the single base illustrated, for operation with a three-thread ringless stocking knitting machine.

In operation, when a yarn, being pulled by a carrier 33, pulls freely off the cone 23, the corresponding spring 57 forces the yarn farthest to the right under its weight member 45, thus, placing the maximum weight and greatest degree of retardation on the yarn; the yarn in this position being at substantially the center of the elongated weight member. As the resistance to pulling the yarn from its source increases, the yarn at the device T forces its spring 57 to the left, as viewed in Fig. 3. During this action, the weight member 45 moves on its fulcrum at the right end of the raised portion 48, Fig. 4, to gradually impose less and less of its weight on the yarn, which, if the tension in it, at the cone, becomes sufficiently great, will entirely move out from beneath the weight member 45 on the high top surface of the strip 47, and move freely across the low top surface at the left of its compartment, as viewed in Fig. 3.

In Fig. 6, the upper two yarns are in positions of substantially maximum retardation by the device, and the lower yarn is in a position of only slight retardation. In Fig. 7, the yarn is in a position relative to its member 45, whereby the weight of the latter is not imposed on the yarn, which passes freely through the device over a low top surface of the strip 47. With the yarn in the latter position, when the tension decreases between the device and the source, the yarn is thus subject to greater lateral bending by the spring 57, which action moves the yarn from a position over the low top surface to the high top surface beneath the element 45, see Fig. 9A.

In the device of Figs. 2, 3, 4, 6 and 7, the yarns must be threaded through the device T from the inlet eyelets 53, beneath the elements 45 and through the outlet eyelets 53. In the modification of the device, shown in Fig. 9, slots 65 in the eyelets 53a and the frame 37a, and slots 66 in the frame opposite the intermediate row of compartments 42a, render it possible to insert the yarns, without threading, as above stated,

by moving the yarns laterally to their length through the slots; the slots 65 being laterally offset from the slots 66 to prevent the possibility of the yarn accidentally working out of the device through the slots, although this is unlikely, 5 because in its position adjacent to the slots, the yarn is under higher tension between the device and the yarn supply. This structure may be mounted on a machine without interrupting the connection of the yarn from the cone to the 10 carrier.

In the modification of the invention illustrated in Figs. 10 to 16, inclusive, the construction and operation of the device Tb are similar to those of the device T above described. However, in the places of the elongated cylindrical weight elements 45, and the strip 47, there are provided upper discoidal elements 45b and lower discoidal elements 47b, respectively, between which the yarn 22 is moved radially, relative to 15 the axes of the discs, by the elongated wire-like springs 57b which are similarly held to the leg 36b, by an adjusting stud 54b, a washer 55b and a stud-holding nut 56b.

The discs 45b and 47b are, respectively, loosely 25 mounted about end standards 67, and about a center standard 68 of a series thereof, on a platform 69, as of sheet metal, which further comprises depending portions 72, of channel section, and upright walls 73, providing a cross-head of 30 relatively shallow substantially U-shape for the structure of generally T-shape of Fig. 10. A slot or slots 70 are provided in the platform 69 to accommodate the upper ends of the springs 57b.

The discs 45b and 47b are preferable of pressed 35 sheet metal, which may be provided with vitreous material surface coatings, as in the case of the strip 47a of Fig. 5, and have oppositely axially curved outer perimeters providing flaring surfaces between which the yarn may freely enter 40 laterally to its length to position between the discs. A sheet-metal member 74, secured to one side wall of the channel 72, has an inverted canopy-like edge 75 over the tops, and opposite 45 the sides, of the springs 57b, to protect the same, and to act as means restraining the springs to the paths of movement thereof. The member 74 also has a slot or slots 71 through which the yarn passes. A portion 76, struck out of the sheet 50 metal of the platform 69, for engaging one side of the trough wall 64, cooperates with other portions 71 of the platform for engaging the opposite side of the trough wall to support the device 55 Tb, similarly to the manner by which the device T of the previous figures is adapted to be held to the trough wall by the jaws 62.

The end standards 67 have lower shank portions, or extensions 78 of reduced diameter, depending through openings in the platform 69 closely fitting the same, and through slots 79 in 60 an upper lateral extension 82 of the upright leg 36b, the slots being along a straight line through the centers of all of the standards. The reduced portions 78 are provided with bushing-like elements 80 which securely fix the standards 67 to the platform 69 by means of a lower head structure 85. A helical spring 84, held about the element 80 and between the extension 82 and the structure 85, exerts a pressure to yieldingly bias 65 and hold the platform 69 and its associated parts 70 against the extension 82 of the leg 36b.

Instead of an extended shank portion of reduced diameter, as in the case of the end standards 67, the center standard 68 has a lower button head portion 86 which serves as a rivet head 75

to hold the shank to the platform, and as a detent for cooperation with any one of a series of apertures 87, in the extension 82, in line with the slots 79.

- 5 Thus, with the platform 69, fixedly related to the trough wall 64, when it is desired to adjust the leg relative to the platform, the leg is grasped and pulled downwardly a slight distance from the platform, against the action of the springs 84.
- 10 This action displaces the button 86 from the aperture 87, which it has been occupying, and permits the leg to be moved relative to the platform in the direction of the slots, after which, upon release of the leg, the springs 84 return the leg 15 to its new position, wherein the button 86 seats in another of the apertures 87 to lock the leg against movement along the slots. This adjustment is provided to adapt the device for cooperation with different yarns, and to vary the movement 20 of the yarns radially of the standards, between the discs. Figs. 15 and 16 illustrate the positions of a yarn relative to the discs, when the device is exerting maximum and minimum retarding action, respectively, against the yarn.
- 25 Figs. 17 and 18 illustrate positions of the yarn, corresponding to the positions thereof in Figs. 15 and 16, respectively, in a modified form of the upper disc comprising loosely related axially concentric inner and outer portions 88 and 89, respectively, whereby, as the yarn is moved inwardly toward the shank, it is first subjected to the weight of the portion 89, as in Fig. 18, and subsequently subjected to the weights of both portions 88 and 89, as in Fig. 17.
- 30 In the modification of the invention shown in Fig. 19, the parts are like those of Fig. 15, except the upper disc 45c, which is provided with an annular under-side bead 92 for more closely confining, or concentrating, the weight of the disc 40 on the yarn. The upper disc structures of Figs. 15, 17 and 19, may readily be slipped on and off the standards, and substituted one for the other on any one lower disc, thus lending further flexibility to the calibration and adjustment of the 45 device in accordance with different needs.

In each of the above-described forms of the invention, the individual tension units may be employed in the separate machine sections of a single-thread knitting machine, and the tension 50 of the individual yarns of separate stockings thereby maintained constant. However, although, maintained constant in the separate stockings, the values of the respective constant tensions might be considerably different, and still 55 produce a good stocking in each section.

In the multiple-thread stocking, the device not only maintains the threads under constant tension but also provides means for maintaining these constant tensions of like value, so that a 60 method of tensioning these yarns relative to each other is provided to prevent different tension in the respective yarns, and to preclude the shadows which might result from separate yarns of non-cooperating or unlike tension. The feature 65 whereby all of the yarns are tensioned at a position in close proximity to each other, represented by the common support for the rollers or disks in the three-thread arrangement illustrated, and emanate from this position of support, also renders the yarns of more nearly equal 70 lengths and otherwise conduces to better cooperation between the yarns in producing the uniform resultant effect in the stocking.

The invention also provides means whereby 75 yarns of different color, gauge, material or other

characteristic may be knitted together, and the tension thereof adjusted and maintained constant at any selected relative value.

The invention may be modified without departing from its spirit and scope, as set forth and 5 claimed.

I claim:

1. A yarn tensioning device, for operation between a yarn supply and a yarn-working member, comprising means for varying the yarn tension, and means actuated by engagement with the yarn between said tension-varying means and the yarn supply for automatically adjusting the effect of said tension varying means on the yarn in accordance with variations in the yarn 15 tension.

2. A yarn tensioning device, for operation between a yarn supply and a yarn-working member, comprising relatively movable elements between which the yarn passes for the imposition 20 by the elements on the yarn of retarding action, and means between said elements and the yarn supply for automatically adjusting the position of the yarn between said elements in accordance with variations of the force required to pull the 25 yarn from the yarn supply whereby said elements impose said retarding action variably on the yarn to maintain the tension in the yarn substantially constant between the elements and the yarn-working member.

3. A yarn tensioning device, for operation between a yarn supply and a yarn-working member, comprising relatively movable elements between which the yarn passes for the imposition by the elements on the yarn of retarding action, and 35 means between said elements and the yarn supply for automatically adjusting the position of the yarn between said elements in accordance with variations of the force required to pull the yarn from the yarn supply whereby said elements impose said retarding action variably on the yarn to maintain the tension in the yarn substantially constant between the elements and the yarn-working member, one of said elements having a surface over which the yarn is adapted to 40 pass, and another of said elements being in the form of a member for biased position against the yarn transversely to the yarn pressing it against said surface, said adjusting means operating to move the yarn transversely of its length between 45 said member and said surface to vary said pressure.

4. A yarn-tensioning device, for operation between a yarn supply and a yarn-working member, comprising relatively movable elements between which the yarn passes for the imposition by the elements on the yarn of retarding action, and means between said elements and the yarn supply for automatically adjusting the position of the yarn between said elements in accordance with 50 variations of the force required to pull the yarn from the yarn supply whereby said elements impose said retarding action variably on the yarn to maintain the tension in the yarn substantially constant between the elements and the yarn-working member, one of said elements having a surface over which the yarn is adapted to pass, and another of said elements being in the form of a member for biased position against the yarn transversely thereto pressing it against said surface, said adjusting means including an element adapted for resiliently-biased operation against the side of the yarn.

5. A yarn-tensioning device, for operation between a yarn supply and a yarn-working mem- 75

ber, comprising relatively movable elements between which the yarn passes for the imposition by the elements on the yarn of retarding action, and means between said elements and the yarn supply for automatically adjusting the position of the yarn between said elements in accordance with variations of the force required to pull the yarn from the yarn supply whereby said elements impose said retarding action variably on the yarn to maintain the tension in the yarn substantially constant between the elements and the yarn-working member, one of said elements having a surface over which the yarn is adapted to pass, and another of said elements being in the form of a member for biased position against the yarn transversely thereto pressing it against said surface, said adjusting means including an elongated resilient element fixed at one end and adapted for lateral bending operation against the side of the yarn.

6. A yarn-tensioning device, for operation between a yarn supply and a yarn-working member, comprising relatively movable elements between which the yarn passes for the imposition by the elements on the yarn of retarding action, and means between said elements and the yarn supply for automatically adjusting the position of the yarn between said elements in accordance with variations of the force required to pull the yarn from the yarn supply whereby said elements impose said retarding action variably on the yarn to maintain the tension in the yarn substantially constant between the elements and the yarn-working member, one of said elements having a surface over which the yarn is adapted to pass, and another of said elements being in the form of a member for biased position against the yarn transversely thereto pressing it against said surface, said adjusting means including a resilient element for imposing its force against the side of the yarn, and means for adjusting the resilient element to vary said force.

7. A yarn-tensioning device, for operation between a yarn supply and a yarn-working member, comprising relatively movable elements between which the yarn passes for the imposition by the elements on the yarn of retarding action, and means between said elements and the yarn supply for automatically adjusting the position of the yarn between said elements in accordance with variations of the force required to pull the yarn from the yarn supply whereby said elements impose said retarding action variably on the yarn to maintain the tension in the yarn substantially constant between the elements and the yarn-working member, one of said elements having a surface over which the yarn is adapted to pass, and another of said elements being in the form of a member for biased position against the yarn transversely thereto pressing it against said surface, said adjusting means including an elongated resilient element fixed at one end and adapted for lateral bending operation against the side of the yarn, and means for adjusting the fixed end of the resilient element to any one of various fixed positions.

8. A yarn-tensioning device, for operation between a yarn supply and a yarn-working member, comprising relatively movable elements between which the yarn passes for the imposition by the elements on the yarn of retarding action, and means between said elements and the yarn supply for automatically adjusting the position of the yarn between said elements in accordance with variations of the force required to pull the

yarn from the yarn supply whereby said elements impose said retarding action variably on the yarn to maintain the tension in the yarn substantially constant between the elements and the yarn-working member, one of said elements having a surface over which the yarn is adapted to pass, and another of said elements being in the form of a member having a surface of vitreous material for pressing the yarn transversely thereto against said surface, said adjusting means operating to move the yarn laterally of its length between said member and said surfaces to vary said pressure.

9. A yarn-tensioning device, for operation between a yarn supply and a yarn-working member, comprising relatively movable elements between which the yarn passes for the imposition by the elements on the yarn of retarding action, and means between said elements and the yarn supply for automatically adjusting the position of the yarn between said elements in accordance with variations of the force required to pull the yarn from the yarn supply whereby said elements impose said retarding action variably on the yarn to maintain the tension in the yarn substantially constant between the elements and the yarn-working member, one of said elements having a surface of vitreous material over which the yarn is adapted to pass, and another of said elements being in the form of a member for pressing the yarn transversely thereto against said vitreous material surface, said adjusting means operating to move the yarn laterally of its length between said members to vary said pressure.

10. A yarn tensioning device, for operation between a yarn supply and a yarn-working member, comprising relatively movable elements between which the yarn passes for the imposition by the elements on the yarn of retarding action, one of said elements being gravity actuated, and means for automatically adjusting the position of the yarn between said elements in accordance with variations in the yarn tension whereby said elements variably impose the retarding action.

11. A yarn tensioning device, for operation between a yarn supply and a yarn-working member, comprising relatively movable elements between which the yarn passes for the imposition by the elements on the yarn of retarding action, and means between said elements and the yarn supply for automatically adjusting the position of the yarn between said elements in accordance with variations of the force required to pull the yarn from the yarn supply whereby said elements impose said retarding action variably on the yarn to maintain the tension in the yarn substantially constant between the elements and the yarn-working member, one of said elements having a surface over which the yarn is adapted to pass, and another of said elements being in the form of an elongated member for biased position against the yarn transversely thereto pressing it against said surface, said adjusting means operating to move the yarn transversely of its length longitudinally of said elongated member to vary said pressure.

12. A yarn tensioning device, for operation between a yarn supply and a yarn-working member, comprising relatively movable elements between which the yarn passes for the imposition by the elements on the yarn of retarding action, and means between said elements and the yarn supply for automatically adjusting the position of the yarn between said elements in accordance with variations of the force required to pull the

yarn from the yarn supply whereby said elements impose said retarding action variably on the yarn to maintain the tension in the yarn substantially constant between the elements and the yarn-
5 working member, one of said elements having a surface over which the yarn is adapted to pass, and another of said elements being in the form of a member for floating position on the yarn trans-
10 versely thereto pressing by its weight the yarn against said surface, said adjusting means operating to move the yarn transversely between said member and said surface to vary said pressure.

13. A yarn tensioning device, for operation be-
15 tween a yarn supply and a yarn-working member,
comprising relatively movable elements between
which the yarn passes for the imposition by the
elements on the yarn of retarding action, and
means between said elements and the yarn sup-
20 ply for automatically adjusting the position of the
yarn between said elements in accordance with
variations of the force required to pull the yarn
from the yarn supply whereby said elements im-
pose said retarding action variably on the yarn
25 to maintain the tension in the yarn substantially
constant between the elements and the yarn-
working member, one of said elements having a
surface over which the yarn is adapted to pass,
and another of said elements being in the form
30 of a cylinder for rotative position on the yarn
transversely thereto pressing it against said sur-
face, said adjusting means operating to move the
yarn laterally of its length longitudinally of said
cylinder to vary said pressure.

14. A yarn tensioning device, for operation be-
35 tween a yarn supply and a yarn-working mem-
ber, comprising relatively movable elements be-
tween which the yarn passes for the imposition
by the elements on the yarn of retarding action,
and means between said elements and the yarn
40 supply for automatically adjusting the position
of the yarn between said elements in accordance
with variations of the force required to pull the
yarn from the yarn supply whereby said elements
impose said retarding action variably on the yarn
45 to maintain the tension in the yarn substantially
constant between the elements and the yarn-
working member, one of said elements having up-
per and lower surfaces gradually merged together
over which the yarn is adapted to move length-
50 wise and laterally, and another of said elements
being in the form of an elongated member dis-
posed over both of said surfaces for biased position
against the yarn transversely thereto pressing it
against said upper surface, said adjusting means
55 operating to move the yarn laterally of its length
longitudinally of said elongated member to lead
the yarn to position between the surface and the
elongated member and to vary its location along
the member in said position.

60 15. A yarn-tensioning device, for operation be-
tween a yarn supply and a yarn-working mem-
ber, comprising relatively movable elements be-
tween which the yarn passes for the imposition
65 by the elements on the yarn of retarding action,
and means between said elements and the yarn
supply for automatically adjusting the position
of the yarn between said elements in accordance
with variations of the force required to pull the
70 yarn from the yarn supply whereby said elements
impose said retarding action variably on the yarn
to maintain the tension in the yarn substantially
constant between the elements and the yarn-
working member, one of said elements having up-
75 per and lower surfaces over the upper surface
of which the yarn is adapted to move lengthwise

and laterally, and another of said elements being
in the form of an elongated member for ful-
crumed position at a shoulder of said upper sur-
face next to said lower surface floating on the
yarn transversely thereto pressing it against the
upper surface, said adjusting means operating
5 to move the yarn longitudinally of said elongated
member to vary said pressure.

16. A yarn-tensioning device, for operation be-
tween a yarn supply and a yarn-working mem-
ber, comprising relatively movable elements be-
tween which the yarn passes for the imposition
by the elements on the yarn of retarding action,
and means between said elements and the yarn
10 supply for automatically adjusting the position
of the yarn between said elements in accordance
with variations of the force required to pull the
yarn from the yarn supply whereby said elements
impose said retarding action variably on the yarn
15 to maintain the tension in the yarn substantially
constant between the elements and the yarn-
working member, one of said elements having a
surface over which the yarn is adapted to pass,
and another of said elements being in the form
20 of a member for floating position on the yarn
transversely thereto pressing by its weight the
yarn against said surface, said adjusting means
operating to move the yarn relative to said mem-
ber to vary said pressure, and a support for said
25 elements adapted to receive any one of a plural-
ity of elements corresponding to said other ele-
ment but of different weight.

17. A yarn-tensioning device, for operation be-
tween a yarn supply and a yarn-working mem-
ber, comprising relatively movable elements be-
tween which the yarn passes for the imposition
by the elements on the yarn of retarding action,
and means between said elements and the yarn
30 supply for automatically adjusting the position
of the yarn between said elements in accordance
with variations of the force required to pull the
yarn from the yarn supply whereby said ele-
ments impose said retarding action variably on
35 the yarn to maintain the tension in the yarn
substantially constant between the elements and
the yarn-working member, one of said elements
having a surface over which the yarn is adapted
to pass, and another of said elements being in
40 the form of an elongated member for floating
position on the yarn transversely thereto pressing
by its weight the yarn against said surface, said
adjusting means operating to move the yarn lon-
gitudinally of said elongated member to vary said
45 pressure, and a support for said elements adapt-
ed to receive any one of a plurality of elements
50 corresponding to said other element but of dif-
ferent weight.

18. A yarn-tensioning device, for operation be-
tween a yarn supply and a yarn-working mem-
ber, comprising relatively movable elements be-
tween which the yarn passes for the imposition
by the elements on the yarn of retarding action,
and means between said elements and the yarn
60 supply for automatically adjusting the position
of the yarn between said elements in accordance
with variations of the force required to pull the
yarn from the yarn supply whereby said elements
impose said retarding action variably on the
65 yarn to maintain the tension in the yarn sub-
stantially constant between the elements and
the yarn-working member, one of said elements
having a surface over which the yarn is adapted
to pass, and another of said elements being in
70 the form of a glass tube having inturned end
edges and adapted for rotative position on the
75

yarn transversely thereto pressing it against said surface, said adjusting means operating to move the yarn laterally of its length longitudinally of said tube to vary said pressure.

- 5 19. A yarn-tensioning device, for operation between a yarn supply and a yarn-working member, comprising relatively movable elements between which the yarn passes for the imposition by the elements on the yarn of retarding action, 10 and means between said elements and the yarn supply for automatically adjusting the position of the yarn between said elements in accordance with variations of the force required to pull the yarn from the yarn supply whereby said elements 15 impose said retarding action variably on the yarn to maintain the tension in the yarn substantially constant between the elements and the yarn-working member, one of said elements having a surface over which the yarn is adapted to pass, 20 and another of said elements being in the form of an annular member for biased position in the direction of its axis against the yarn pressing it against said surface, said adjusting means operating to move the yarn transversely of its length 25 substantially radially of said annular member.

20. A yarn-tensioning device, for operation between a yarn supply and a yarn-working member, comprising relatively movable elements between which the yarn passes for the imposition 30 by the elements on the yarn of retarding action, and means between said elements and the yarn supply for automatically adjusting the position of the yarn between said elements in accordance with variations of the force required to pull the 35 yarn from the yarn supply whereby said elements impose said retarding action variably on the yarn to maintain the tension in the yarn substantially constant between the elements and the yarn-working member, said elements being of annular 40 form disposed in adjacent axial relation and yieldably biased axially together for pressing against the yarn, said adjusting means operating to move the yarn transversely of its length substantially radially of said elements.

- 45 21. A yarn-tensioning device, for operation between a yarn supply and a yarn-working member, comprising relatively movable elements between which the yarn passes for the imposition by the elements on the yarn of retarding action, 50 and means between said elements and the yarn supply for automatically adjusting the position of the yarn between said elements in accordance with variations of the force required to pull the 55 yarn from the yarn supply whereby said elements impose said retarding action variably on the yarn to maintain the tension in the yarn substantially constant between the elements and the yarn-working member, one of said elements having a surface over which the yarn is adapted 60 to pass, and another of said elements being in the form of an annular member having a surface for biased position in the direction of its axis toward said first surface, one of said surfaces having a portion of undulate contour, said adjusting means 65 operating to move the yarn transversely of its length substantially radially of said annular member.

22. A yarn-tensioning device, for operation between a yarn supply and a yarn-working member, comprising relatively movable elements between which the yarn passes for the imposition by the elements on the yarn of retarding action, and means between said elements and the yarn supply for automatically adjusting the position 75 of the yarn between said elements in accordance

with variations of the force required to pull the yarn from the yarn supply whereby said elements impose said retarding action variably on the yarn to maintain the tension in the yarn substantially constant between the elements and the yarn-working member, said elements being of annular form disposed in adjacent axial relation and yieldably biased axially together for pressing against the yarn and one of said elements embodying members movable relative to each other, said adjusting means operating to move the yarn transversely of its length substantially radially of said annular elements.

23. A yarn-tensioning device, for operation between a yarn supply and a yarn-working member, comprising relatively movable elements between which the yarn passes for the imposition by the elements on the yarn of retarding action, and means between said elements and the yarn supply for automatically adjusting the position of the yarn between said elements in accordance with variations of the force required to pull the yarn from the yarn supply whereby said elements impose said retarding action variably on the yarn to maintain the tension in the yarn substantially constant between the elements and the yarn-working member, one of said elements having a surface over which the yarn is adapted to pass, and another of said elements being in the form of an annular member for biased position in the direction of its axis against the yarn pressing it against said surface, said adjusting means operating to move the yarn transversely of its length substantially radially of said annular member.

24. A yarn-tensioning device, for operation between a yarn supply and a yarn-working member, comprising relatively movable elements between which the yarn passes for the imposition by the elements on the yarn of retarding action, means between said elements and the yarn supply for automatically adjusting the position of the yarn between said elements in accordance with variations of the force required to pull the yarn from the yarn supply whereby said elements impose said retarding action variably on the yarn to maintain the tension in the yarn substantially constant between the elements and the yarn-working member, one of said relatively movable elements including relatively movable portions for successively imposing different retarding action on the yarn in accordance with the position of the yarn between said elements.

25. A yarn-tensioning device, for operation between a yarn supply and a yarn-working member, comprising relatively movable elements between which the yarn passes for the imposition by the elements on the yarn of retarding action, means between said elements and the yarn supply for automatically adjusting the position of the yarn between said elements in accordance with variations of the force required to pull the yarn from the yarn supply whereby said elements impose said retarding action variably on the yarn to maintain the tension in the yarn substantially constant between the elements and the yarn-working member, a support for said elements and for said yarn-adjusting means, and means for changing the position of the elements on the support.

25. A yarn-tensioning device, for operation between a yarn supply and a yarn-working member, comprising relatively movable elements between which the yarn passes for the imposition by the elements on the yarn of retarding action, means between said elements and the yarn supply for automatically adjusting the position of the yarn between said elements in accordance with variations of the force required to pull the yarn from the yarn supply whereby said elements impose said retarding action variably on the yarn to maintain the tension in the yarn substantially constant between the elements and the yarn-working member, a support for said elements and for said yarn-adjusting means, and spring-and-detent means for yieldably releasably positively holding the elements in any one of a plurality of selective positions on the support relative to said yarn-adjusting means.

26. A yarn-tensioning device, for operation between a yarn supply and a yarn-working member, comprising relatively movable elements between which the yarn passes for the imposition by the elements on the yarn of retarding action, means between said elements and the yarn supply for automatically adjusting the position of the yarn between said elements in accordance with

variations of the force required to pull the yarn from the yarn supply whereby said elements impose said retarding action variably on the yarn to maintain the tension in the yarn substantially constant between the elements and the yarn-working member, a support for said elements and for said yarn-adjusting means, the latter including an elongated wire-like spring for fixed position adjacent to one end and lateral bending movement carrying its free end along an arcuate path, and means on the support for protecting said end along said path.

27. A yarn-tensioning device, for operation between a yarn supply and a yarn-working member, comprising relatively movable elements between which the yarn passes for the imposition by the elements on the yarn of retarding action,

means between said elements and the yarn supply for automatically adjusting the position of the yarn between said elements in accordance with variations of the force required to pull the yarn from the yarn supply whereby said elements impose said retarding action variably on the yarn to maintain the tension in the yarn substantially constant between the elements and the yarn-working member, a support for said elements and for said yarn, adjusting means including eyelets 5 for leading the yarn to and from the elements and including slotted portions adjacent to the eyelets and to the elements for positioning the yarn in the eyelets and between the elements by moving it laterally into position. 10 15
